HOISTING MECHANISM

Robert C. Osgood, Claremont, N. H., assignor to
 Sullivan Machinery Company, a corporation
 of Massachusetts

Application December 22, 1933, Serial No. 703,585

15 Claims. (Cl. 254—185)

This invention relates to hoisting mechanisms, and more particularly to improvements in the drum drive and control means of a hoisting mechanism of the plural drum type.

5 An object of this invention is to provide an improved hoisting mechanism. Another object is to provide an improved hoisting mechanism of the plural drum type having improved drum control means. A further object is to provide an improved control means for the drum driving means and the drum braking means of such a hoisting mechanism. Yet another object is to provide improved operator-controllable power devices controlling the drum driving and braking means of 10 a hoist of the plural drum type. These and other objects will, however, hereinafter more fully appear.

In the accompanying drawings there is shown for purposes of illustration one form which the 15 invention may assume in practice.

20 In these drawings,—

Fig. 1 is a plan view of a hoisting mechanism of the plural drum type having embodied therein in the illustrative form of the improved control 25 means.

Fig. 2 is a side elevational view of the hoisting mechanism shown in Fig. 1.

Fig. 3 is an end elevational view of the hoisting mechanism.

30 Fig. 4 is a central longitudinally extending vertical sectional view taken substantially on line 4—4 of Fig. 1.

Fig. 5 is a detail sectional view showing one of the power cylinders.

35 Fig. 6 is a perspective view showing the improved control means.

Fig. 7 is a detail sectional view taken substantially on line 7—7 of Fig. 6.

Fig. 8 is a detail sectional view showing the 40 fluid control valve.

In this illustrative embodiment of the invention the improved control means generally designated 1 is shown embodied in a hoisting mechanism generally designated 2 which is herein preferably of the same general type as that disclosed 45 in my Patent No. 1,740,707, granted Dec. 24, 1929, although it will be evident that the improved control means may be associated with hoists of various other types.

50 The hoisting mechanism disclosed herein comprises a base frame 3 having upstanding end supports 4 and 5. Secured to one end of the base frame 3 is a supplemental base frame 6 which forms a support for a motor 7. Secured to the 55 power shaft 8 of this motor, as shown in Fig. 4,

is a motor pinion 9 meshing with an internal gear 10 keyed to one end of a longitudinally extending horizontal driving or transmission shaft suitably journaled within bearings supported within the upstanding end supports 4 and 5. Keyed adjacent to the opposite ends of the shaft 11 are spur drive pinions 12 and 13 which constantly mesh respectively with planetary drum driver gears 14 and 15, each of which is journaled on a stub shaft 16 carried by the cable winding drums 17 and 18, 10 respectively. These drums are rotatably mounted on the drive shaft 11 and are herein arranged in substantially end abutting relation between the upstanding supports 4 and 5. The gears 14 and 15 constantly mesh respectively with internal 15 gears 19 and 20 suitably secured to reaction or "clutch control" members 21 and 22, respectively, these reaction members each being provided with a hub portion journaled within the bearings likewise carried within the upstanding supports 15 20 4, 5. Each of the gear portions secured to the reaction members 21 and 22 is externally grooved as at 23 and suitable brake bands 24 and 25, respectively cooperate with the bottoms of these grooves. In this instance, formed on the adjacent ends of the drums are flanged portions having external grooves 26 with which suitable "spin control" brake bands 27 and 28 respectively cooperate. Suitable mechanism for controlling each 25 brake band is provided which the operator may tighten selectively to hold either of the reaction 30 members 21, 22 stationary or loosen to permit free rotation of the latter and for applying the brake bands 27, 28 for braking drum rotation when the reaction member control brakes are released, 35 as hereinafter described.

In the operation of this hoisting mechanism, it will be noted that when the motor is running, the transmission shaft 11, and consequently the drive pinions 12 and 13, are rotated, though the winding drums 17 and 18 loosely journaled on this shaft may be idle if the brake bands 24 and 25 controlling the reaction members 21 and 22 are released so that the reaction members may freely rotate. If it is desired to rotate the drum 17 to wind in its cooperating cable, the brake band 24 controlling rotation of the reaction member 21 is applied, consequently preventing rotation of the internal gear 19. The pinion 12 then causes the planetary gear 14 to roll around the internal gear 19 as a trackway and move with it the winding drum 17. The winding drum 18 is free to pay out its cooperating cable under the control of the brake band 28, the brake band 25 controlling the reaction member 22 being re- 50 55

- leased at this time, and the reaction member 22 being freely rotatable. If it is desired to rotate the drum 18 to wind in its cooperating cable and to pay out the cable cooperating with the drum 17, the brake band controlling the reaction member 21 is released, permitting rotation of the drum 17 under the control of the brake band 27. The brake band 25 controlling rotation of the reaction member 22 is then applied 10 and the internal gear 20 held stationary, the pinion 13 then causing the planetary gear 15 to roll around the internal gear 20 as a trackway and causing the drum 18 to revolve therewith. It will therefore be evident that through suitable application of the brake bands 24 and 25, the winding drums 17 and 18 may be selectively positively driven from the motor 7; and that when these brake bands are released, the winding drums may remain idle during running of the motor. 15
- 20 In the present instance, the brake bands 27, 28 control undesirable spinning of the drums when the brake bands controlling the reaction members 21 and 22 are released and merely constitute drag frictions.
- 25 Now referring to the improved drum control means, it will be noted that arranged at the end of the base adjacent the upstanding support 5 is a pair of power cylinders 30 and 31 each pivotally mounted at its rear end at 32 on a bracket 33 attached to the adjacent end of the support 3. Each of these cylinders has reciprocably mounted therein a piston 34, each having a forwardly projecting piston rod 35 projecting through a stuffing box 36 carried by the front head 37 of the cylinder. Arranged between the front cylinder head and the piston 34 and encircling the piston rod is a coil spring 38 for returning the piston 34 to its rearmost position when the cylinder at the rear side of the piston 40 is vented to atmosphere. The forward or outer end of each cylinder at the front side of the piston is vented to atmosphere through a port 39. The outer ends of the piston rods 35, 35 are pivotally connected at 40 to levers 41 and 42, respectively. The lever 41 is fixed to a tubular shaft 43 journaled in bearing brackets 44 secured to the support 3, while the lever 42 is fixed to a shaft 45 journaled within the tubular shaft 43 and a bearing bracket 46 similar to the brackets 44 and likewise secured to the support 3. Fixed to the tubular shaft 43 between the right hand bearing supports 44, 44 is a lever 47 pivotally connected at 48 to a rod 49 in turn pivotally connected at its upper end at 50 to a lever 51. This lever is pivotally connected at 52 to one end of the brake band 25 and at 53 to a toggle link 54 in turn pivotally connected at 55 to the opposite end of the brake band. Fixed to the end of the inner shaft 45 remote 50 from the lever 42 is a lever 56 pivotally connected at 57 to a rod 58 in turn connected through lever mechanism similar to that above described to the brake band 24. The brake bands 27 and 28 which control spinning of the drums are provided with similar lever operating mechanism and the brake band 27 is operated from the inner shaft 45 by a lever 59 fixed to the shaft and pivotally connected at 60 to a rod 61, while the brake band 28 is operated 65 from the tubular shaft 43 by a lever 62 fixed to the shaft and pivotally connected at 63 to a rod 64. The levers 47, 56, 59 and 62 are arranged on their respective shafts so that when one shaft is rotated the brake band for one drum is released while the other is applied, while when

the other shaft is rotated, one brake band for one drum is applied while the other is released. In other words, when the drive control brake band 24 for the drum 17 is applied, the spin control brake band 27 for that drum is released, while when the spin control brake band 28 for the drum 18 is applied, the drive control brake band 25 for that drum is released. 5

The means for supplying fluid to the power cylinders 30, 31 and for controlling such fluid supply herein comprises a valve casing 65 carried by a plate 66 secured to the upstanding support 5, and this valve casing has arranged therein a usual four-way valve having an operating lever 67. Connected to the opposite sides of the valve casing 65 are flexible pipe connections 68 and 69 leading to the rear ends of the power cylinders 30 and 31, respectively. Connected to the bottom of the valve casing is a fluid supply pipe 10, this fluid supply pipe communicating with the interior of the valve casing through a restricted opening. Arranged at the top of the valve casing is a free exhaust pipe 71. 10

When the handle 67 of the four-way valve is in the full line position shown in Fig. 3, pressure fluid is supplied through the pipe connection 68 to the rear end of the power cylinder 30, thereby moving the piston 34 outwardly to swing the lever 41 thereby to rotate the tubular shaft 43 in a direction to release the brake band 28 and apply 25 the brake band 25, and as a result the reaction member 22 is held stationary to effect drive of the drum 18. The piston 34 of the power cylinder 31 is at that time held in its released position by the coil spring 38, and as a result, the lever 42 is held 30 in such a position as to maintain the drive control brake band 24 released while the spin control brake band 27 is applied, and as a result maintaining the drum 17 disconnected from its drive with the spinning brake applied with sufficient pressure to prevent undesirable spinning of the drum. When the handle 67 of the four-way valve is 35 swung into the dotted line position shown in Fig. 3, pressure fluid is supplied through the pipe connection 69 to the power cylinder 31, thereby moving the piston forwardly to effect actuation through the links and levers of the brake bands 24 and 27 so that the brake band 24 is applied and the brake band 27 is released. At the same time the power cylinder 30 is vented to atmosphere, 40 and the piston thereof is moved into its released position by the coil spring 38 thereby to apply the spin control brake band 28 and to release the drive control brake band 25, and as a result the drum 18 is disconnected from its drive while the 45 spinning brake 28 is applied. It will thus be seen that one or the other of the drums is always connected to its drive while the other drum is disconnected from its drive with its spinning brake applied under the manual control of a common 50 operating element. It will also be noted that the parts are so arranged that the drums are disconnected from their drive before the spinning brakes are applied, the drum drive control brake being first released and upon release of the same 55 the spinning brake is applied. 60

Although there is shown but single acting power cylinders for the brake control means, it will be evident that if desired the springs may be omitted and the pistons actuated by pressure fluid in both 70 directions, and under certain conditions but a single double acting power cylinder may be employed for controlling through suitable linkage the brakes of both drums. It has been found, however, under the conditions to which the hoist- 75

ing mechanism disclosed herein is particularly adapted, the springs 38 act to apply the spinning brakes and release the drum drive control brakes in a more desirable manner.

5 While there is in this application specifically described one form which the invention may assume in practice, it will be understood that this form of the same is shown for purposes of illustration and that the invention may be embodied in 10 various other forms without departing from its spirit or the scope of the appended claims.

What I claim as new and desire to secure by Letters Patent is:

1. In a hoisting mechanism, relatively rotatable 15 cable winding drums, drum driving means, drive control means for connecting said drums to said driving means, drum braking means, power devices for controlling said drive control means and said braking means comprising a pair of motors, 20 one motor controlling the control and braking means for one drum and the other motor controlling the control and braking means for the other drum, and common control means for said power devices.

25 2. In a hoisting mechanism, relatively rotatable cable winding drums, drum driving means, drive control means for connecting said drums to said drive means, drum braking means, power devices for controlling said drive control means and said 30 braking means comprising a pair of motors, one motor controlling the control and braking means for one drum and the other motor controlling the control and braking means for the other drum, whereby when one drum is connected to its drive 35 35 the other drum is braked, and common control means for said power devices.

3. In a hoisting mechanism, relatively rotatable cable winding drums, drum driving means, drive control means for connecting said drums to said 40 driving means, drum braking means, power devices including a pair of motors, one individual to the control and braking means for each drum, and means actuated by said motors for controlling said drive control means and said braking means, 45 and common control means for said motors.

4. In a hoisting mechanism, relatively rotatable cable winding drums, drum driving means, drive control means for connecting said drums to said 45 driving means, drum braking means, power devices for controlling said drive control means and said braking means comprising a pair of power cylinders having pistons reciprocable therein, one power cylinder controlling the control and braking means for one drum and the other power cylinder controlling the control and braking means for the other drum, and common control means for said power devices.

5. In a hoisting mechanism, relatively rotatable cable winding drums, drum driving means, 50 drive control means for connecting said drums to said driving means, drum braking means, power devices for controlling said drive control means and said braking means comprising a pair of power cylinders having pressure fluid actuated pistons reciprocable therein, one power cylinder controlling the control and braking means for one drum and the other power cylinder controlling the control and braking means for the other drum, and common control means for said power devices comprising a common control valve for regulating the flow of pressure fluid to said power cylinders.

6. In a hoisting mechanism, relatively rotatable cable winding drums, drum driving means, 55 drive control means for connecting said drums to

to said driving means, drum braking means, power devices controlling said drive control means and said braking means comprising power cylinders, one individual to the control and braking means for each drum, a piston reciprocable in each cylinder, said pistons being moved in one direction in said cylinders by pressure fluid, and springs acting on said pistons for moving the latter in the opposite direction.

7. In a hoisting mechanism, relatively rotatable cable winding drums, drum driving means, drive control means for connecting said drums to said driving means, drum braking means, power devices controlling said drive control means and said braking means comprising power cylinders, one individual to the control and braking means for each drum, a piston reciprocable in each cylinder, said pistons being moved in one direction in said cylinders by pressure fluid, and springs acting on said pistons for moving the latter in the opposite direction, said pistons being moved in the first mentioned direction by pressure fluid to actuate said drive control means and said pistons being moved in the opposite direction by said springs to actuate said drum braking means.

8. In a hoisting mechanism, a cable winding drum, drum driving means, drive control means for connecting said drum to said driving means, drum braking means, a power cylinder, a piston reciprocable therein operatively connected with said drive control and braking means, means for supplying pressure fluid to said power cylinder to move said piston in one direction to actuate said drive control means to connect said drum to its drive, and a spring acting on said piston for moving the latter in the opposite direction to release said drive control means and to apply said braking means.

9. In a hoisting mechanism, relatively rotatable cable winding drums, drum driving means, drive control means for connecting said drums to said driving means, power devices for controlling said drive control means comprising a pair of motors, one motor controlling the drive control means for one drum and the other the drive control means for the other drum, and common control means for said motors whereby when the drive control means for one drum is connected the other is always released.

10. In a hoisting mechanism, relatively rotatable cable winding drums, drum driving and control means, drum braking means, power devices for controlling said drum braking means comprising a pair of motors, one controlling the braking means for one drum and the other controlling the braking means for the other drum, and common control means for said motors whereby when one braking means is applied the other is always released.

11. In a hoisting mechanism, a cable winding drum, drum driving means, drive control means for connecting said drum to said driving means, drum braking means, and motor operated devices for applying said braking means and connecting said control means whereby when said control means is connected the braking means is always released and vice versa, said motor operated devices including a power cylinder, a piston reciprocable therein, means for supplying pressure fluid to said power cylinder to move said piston in one direction and a spring acting on said piston for moving the latter in the opposite direction when the pressure fluid actuated end of said cylinder is vented to atmosphere.

12. In a hoisting mechanism, relatively rotatable cable winding drums, drum driving means, drive control means for connecting said drums to said driving means, power operated means for controlling said drum drive control means comprising a pair of separate power devices, one power device controlling the drive control means for one drum and the other the drive control means for the other drum, and separate transmission means between said power devices respectively and said drive control means for said drums, and common control means for said power devices controlling supply of operating medium thereto whereby when the drive control means of one drum is connected the other is always released.
13. In a hoisting mechanism, relatively rotatable cable winding drums, drum driving and control means, drum braking means, separate power operated means for controlling said drum braking means comprising a pair of separate power devices, one controlling the braking means for one drum and the other controlling the braking means for the other drum, and separate transmission means between said power devices, respectively, and said drum braking means, and common control means for said power devices whereby when one braking means is applied the other is always released.
14. In a hoisting mechanism, relatively rotatable winding drums, drum driving means, drive control means for connecting said drums to said driving means, drum braking means, power operated means for controlling said drive control means and said braking means comprising a pair of separate power devices, one power device controlling the drive control means and braking means for one drum and the other the drive control means and braking means for the other drum, each power device effecting alternatively connection of the drive control and application of the braking means for its respective drum, separate transmission means between said power devices, respectively, and said drive control and braking means for said drums, and common control means for said power devices whereby when the drive control for one drum is connected and the braking means therefor is released the drive control means for the other drum is always released and the braking means for the latter drum is always applied.
15. In a hoisting mechanism, a cable winding drum, drum driving means, drive control means for connecting said drum to said driving means, drum braking means, and motor operated devices for applying said braking means and connecting said control means whereby when said control means is connected the braking means is always released and vice versa, said motor operated devices including a pressure fluid actuated power device, means for supplying pressure fluid to said power device to move the power element thereof in one direction, and a spring acting on said movable power element for moving said power element in the opposite direction when the pressure fluid in said power device is vented to atmosphere.

ROBERT C. OSGOOD.
